[57] CLAIM

The ornamental design for a pneumatic orbital polisher,
as shown and described.

DESCRIPTION

FIG. 1 is a perspective view of my new design for a
pneumatic orbital polisher as seen from the top and a
first side; and

FIG. 2 is an elevational view of a second, opposite side
thereof relative to FIG. 1.

The fragmentary elements shown in FIGS. 1 and 2 are
for illustrative purposes only.
